US0D1073035S

(12) **United States Design Patent** (10) Patent No.: **US D1,073,035 S**
(45) Date of Patent: ** Apr. 29, 2025

(54) **DEHUMIDIFIER**

(71) Applicant: **Guangzhou DongAo Electrical Co., Ltd.**, Guangdong (CN)

(72) Inventor: **Xijie Zhang**, Guangzhou (CN)

(73) Assignee: **Guangzhou DongAo Electrical Co., Ltd.**, Guangzhou (CN)

(**) Term: **15 Years**

(21) Appl. No.: **29/858,300**

(22) Filed: **Oct. 31, 2022**

(30) **Foreign Application Priority Data**

May 5, 2022 (CN) 202230257604.X

(51) LOC (15) Cl. **23-04**
(52) U.S. Cl.

USPC **D23/359**

(58) **Field of Classification Search**

USPC D23/356, 359, 360, 364, 333, 332, 354
CPC F24F 2006/008; F24F 6/00; F24F 6/10;
F24F 2221/12

See application file for complete search history.

(57) **CLAIM**

The ornamental design for a dehumidifier, as shown and described.

DESCRIPTION

FIG. 1 is a front view of a dehumidifier showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top front left perspective view thereof; and,

FIG. 8 is a top rear right perspective view thereof.

The broken lines in the figures show portions of the dehumidifier that form no part of the claimed design.

1 Claim, 8 Drawing Sheets
